UNITED STATES PATENT OFFICE

FREDERICK E. MARKERT, OF BOGOTA, NEW JERSEY, ASSIGNOR TO JOHN BOYLE & COMPANY, INCORPORATED, OF NEW YORK, N. Y., A CORPORATION OF NEW YORK

AWNNG FIXTURE

Application filed March 6, 1930. Serial No. 433,572.

This invention relates to an improved awning fixture adapted to be readily applied to a bent rod to be used as an awning frame and serve as a means whereby a spearhead or other appropriate ornamental device may be secured to the frame at each end of the awning.

One object of the invention is to provide a simple fixture which may be used at either end of the frame and through which the rod may be threaded so that the fixture may be slipped over either end of the rod and moved therealong within the pocket in which the rod is enclosed, to and around the bend in the rod where it may be easily secured in place through the opening in the pocket commonly provided to receive the cord by which the frame is raised. Another object of the invention is to provide the fixture with an improved fastening means whereby the rod may be firmly clamped within the fixture. The fastening means may comprise a set screw having its axis spaced from the rod-contacting surface of the fixture a distance somewhat greater than half the diameter of the rod, whereby the rod may be clamped between the set screw and the fixture. By providing the fixture with oppositely-disposed threaded openings for the set screw the device may be used at either end of the awning frame with the set screw at the top so as to be accessible through the opening in the pocket of the awning.

In the accompanying drawings illustrating the preferred and a modified form of the invention,—

Figure 1 is a perspective view of an awning of a well-known type having the invention applied thereto.

Fig. 2 is a horizontal sectional view through the pocket of the awning immediately above the awning frame.

Fig. 3 is an enlarged horizontal sectional view through a portion of the awning structure illustrated in the lower left-hand corner of Fig. 2.

Fig. 4 is a view in cross-section along the line 4—4 of Fig. 3 in the direction indicated by the arrows.

Fig. 5 is a view in cross-section along the

line 5—5 of Fig. 3 in the direction indicated by the arrows.

Fig. 6 is a plan view of a portion of the left end of the awning frame, and a horizontal sectional view of the fixture, indicating the manner in which the rod may be threaded through the fixture, thus permitting the fixture to be moved along the rod and around the bend at its angle to the position indicated in Fig. 2.

Fig. 7 is a horizontal cross-sectional view through a fixture of modified form.

Fig. 8 is a vertical cross-sectional view through a portion of the awning and awning frame along the line 8—8 of Fig. 2 viewed in the direction indicated by the arrows.

Referring first to Figs. 1 and 2, the awning 20 may be supported in any appropriate manner at the top and may have the usual pocket 21 extending around its front and two sides near the bottom to receive a frame 22, which may comprise a simple rod of circular form in cross-section having bends 23, 23' between its center and opposite ends to form the angles at the corners of the awning. One manner of forming the pocket 21 for the frame 22 is indicated in detail in Fig. 8. The awning, if desired, may be provided with the usual scalloped edging 24.

The ends of the frame 22 are commonly threaded and capped with fittings 25 having eyes 26 thereon by which the frame may be pivotally secured to wall fixtures of any suitable character.

The stitching 27 along the upper margin of the pocket for the frame 22 is usually omitted for a short space near each end of the awning so as to provide openings 28 (Figs. 1 and 2) through which cords secured to the end portions of the frame may pass to the pulleys (not shown) secured to the wall underneath the upper portion of the awning.

The invention now to be described comprises a fixture 29 which may be applied to either of the bends 23, 23', as a means whereby a spearhead or other suitable ornamental device 30 may be secured to the frame at either end of the awning. This fixture, the preferred form of which is illustrated in

60

Fig. 3, is an angular device having one leg 31 to be applied to one leg of the angle of the awning frame at the bend 23, and another leg 32 to be applied to the other leg of the awning frame. Described in general terms, the leg 31 of the fixture may be of any suitable form to make contact with the awning frame and determine its position in one direction. The leg 32 may be of any suitable form to be applied to the other leg of the awning frame and determine the position of the fixture in another direction. As herein disclosed, the leg 31 is of tubular form having a front portion 33 (Fig. 4) which may serve as a saddle to straddle the adjacent part of the frame 22. The leg 32 is also in the form of a saddle 34 (Fig. 5) to straddle the adjacent part of the rod or frame 22.

It is important that the two legs 31, 32 of the fixture be of some such form as to make it possible to thread the rod through the fixture as indicated in Fig. 6, and pass the fixture along the rod through the pocket 21 to the position indicated in Figs. 2 and 3. It is for this reason that one of the legs, the leg 32 in the form of the invention illustrated in Fig. 3, should be open along one side instead of being tubular like the leg 31. The importance of thus having at least one of the legs open is clearly indicated in Fig. 6.

One satisfactory means of securing the fixture to the frame as indicated in Figs. 3 and 4 may comprise a set screw 35 in a threaded opening 36 tapped in a boss 37 extending upwardly from the top surface of the leg 31 of the fixture. The axis of this set screw should be substantially at right angles to a plane determined by the axes of the two legs of the fixture, and the axis of the screw should be spaced from the inner surface of the front wall of said leg 31 a distance somewhat greater than half the diameter of the rod 22, whereby the screw will make contact with the rod at a point intermediate its center and its inner surface, thus causing the rod to be firmly clamped between the screw and the wall of the saddle-like portion 33 of the fixture, as best illustrated in Fig. 4.

In order that the same fixture may be used at either end of the awning and secured by a set screw having its threaded end extending upwardly so as to be inserted and removed through the openings 28 (Figs. 1 and 2) of the awning, the leg 31 of the fixture may be provided with a second threaded opening 36' in a boss 37' located directly opposite to the threaded opening 36 in the boss 37. If therefore, the fixture is applied to the right end of the awning frame, the set screw 35 may be inserted in the opening 36' instead of in the opening 36, so that its threaded end will be exposed at the top of the fixture as indicated in Fig. 2. As thus constructed the two fixtures used at the opposite ends of an awning are identical, yet the set screw in each fixture

may be properly positioned for access through the pockets 28.

The fixture 29 and spearhead or other ornament 30 may be provided with any appropriate fastening elements whereby they may be secured together. In the form of the invention illustrated in Fig. 3 the fixture is provided with a threaded lug 38 adapted to be passed through an eyelet 39 in the awning and the spearhead 30 is provided with a threaded socket 40 to receive the lug. When the spearhead is screwed onto the lug 38 of the fixture, the eyelet 39 will be tightly clamped between the adjacent surfaces so as to prevent dust, moisture, etc. from entering the pocket in the awning for the frame 22.

In Fig. 7 of the drawing is disclosed a modified form of the invention in which the fixture is provided with a threaded opening 38' adapted for use when the spearhead or other ornament to be secured to the awning frame is provided with a correspondingly threaded lug instead of a socket.

It will be apparent that fixtures embodying the invention may readily be applied to awnings already in use as well as to those newly manufactured, since they may be added by merely unscrewing the caps 25 from the ends of the frame, slipping the fixtures over the ends of the frame, and passing them along the rods 22, through the pockets 21, to and around the bends 23, 23' of the frame to the positions indicated in Fig. 2, and they may be secured by inserting the set screws through the pockets 28. The awning may then be perforated and supplied with eyelets 39 through which the spearheads or other ornaments and the fixtures may be secured together by any appropriate fastening means.

The invention is not intended to be limited to the specific forms herein selected for purposes of illustration, but should be regarded as including modifications and variations thereof within the scope of the appended claims.

What is claimed is:

1. An awning fixture comprising an angular device adapted to be secured to the bent portion of a rod to be used as an awning frame, said fixture having a saddle-like leg to straddle the outer surface of one leg of the frame at the bend, a stop to make contact with and determine the position of the fixture with respect to the other leg of the frame at the bend, a separate fastening element, adapted to be readily made effective or ineffective at will, by which the saddle-like leg may be clamped against the portion of the frame which it straddles, and a fastening element whereby an ornamental device may be secured to the fixture.

2. An awning fixture comprising an angular device adapted to be secured to the bent portion of a rod to be used as an awning frame, said fixture having a saddle-like leg to

straddle the outer surface of one leg of the frame at the bend, a second saddle-like leg to embrace the inner surface of the other leg of the frame at the bend, a fastening element to clamp the fixture to the rod, and a fastening element whereby an ornamental device may be secured to the fixture.

5 3. An awning fixture, as defined by claim 2, having, as its rod-clamping fastening element, a set screw of which the axis is perpendicular to a plane determined by the axes of the two saddle-like legs of the fixture, said set screw being located in one of said saddle-like legs with its center spaced from the inner surface of the leg a distance slightly greater than the diameter of the rod on which the fixture is to be used, whereby the rod may be firmly clamped in said leg by the set screw.

10 4. An awning fixture comprising an angular device having one tubular leg and one saddle-shaped leg adapted to be threaded on and around the bent portion of a rod to be used as an awning frame, a set screw in said tubular leg having its axis perpendicular to a plane determined by the axes of the two legs of the fixture, the axis of said set screw being spaced from the inner surface of the outer wall of said tubular leg a distance slightly greater than half the diameter of the rod on which the fixture is to be used, whereby the rod may be firmly clamped between the set screw and the outer wall of said tubular leg, and a fastening element whereby an ornamental device may be secured to the fixture.

15 5. An awning fixture comprising an angular device of tubular form adapted to encircle and be moved along a bent rod to be used as an awning frame, from one end to and around the bend in the rod at the corresponding end of the frame, said fixture having two legs to make contact respectively with the legs of the rod near said bend, a set screw having its axis perpendicular to a plane determined by the axes of the legs of the fixture, said set screw being located in one of said legs with its center spaced from its rod-contacting surface a distance slightly greater than half the diameter of the rod so that the rod may be firmly clamped in the leg by the set screw, and a fastening element whereby an ornamental device may be secured to the fixture.

20 6. An awning fixture, as defined by claim 5, having oppositely-disposed threaded openings for its set screw, so that the fixture may be used at opposite ends of an awning frame by inserting the screw in the appropriate opening.

25 In witness whereof, I have hereunto signed
60 my name.

FREDERICK E. MARKERT.
